UNITED STATES PATENT OFFICE.

FRANKLIN F. KNOUS, OF NEW HAVEN, CONNECTICUT, ASSIGNOR TO WINCHESTER REPEATING ARMS CO., OF NEW HAVEN, CONNECTICUT, A CORPORATION.

AUTOMATIC FIREARM.

933,254.

Specification of Letters Patent. Patented Sept. 7, 1909.

Application filed February 23, 1909. Serial No. 479,373.

To all whom it may concern:

Be it known that I, FRANKLIN F. KNOUS, a citizen of the United States, residing at New Haven, in the county of New Haven and State of Connecticut, have invented a new and useful Improvement in Automatic Firearms; and I do hereby declare the following, when taken in connection with the accompanying drawings and the numerals of reference marked thereon, to be a full, clear, and exact description of the same, and which said drawings constitute part of this specification, and represent, in—

Figure 1 a broken view partly in side elevation and partly in vertical section of a gun constructed in accordance with my invention, shown as closed and with the hammer "down". Fig. 2 a detached view in side elevation of the trigger, a portion of which is broken away to show the socket formed in it for the reception of a spring-plunger forming a yielding trigger-stop. Fig. 3 a detached plan view of the sear. Fig. 4 a view thereof in side elevation. Fig. 5 a view in side elevation of the volley-fire lever. Fig. 6 a reverse broken plan view of the breech-bolt which has a balancing extension in the form of two forwardly extending arms. Fig. 7 a detached view on an enlarged scale of the yielding trigger stop.

My invention relates to an improvement in that class of shoulder arms which have heretofore been commonly designated as "automatic" for the reason that they have been constructed so that the explosion of the cartridge has been utilized as the motive power for the extraction of the spent shell, the introduction of another cartridge into the cartridge chamber of the gun-barrel and the cocking of the hammer preparatory to the explosion of the cartridge so introduced. Automatic guns of the class above referred to have been operated by the gases of explosion as well as by the recoil of explosion. Strictly speaking these shoulder guns are semi-automatic rather than "automatic" for the reason that the hammer is not automatically released for firing. Indeed much ingenuity has been expended in safe-guarding them against volley-firing by constructing them so that the trigger must be consciously released by the user after each shot.

The object of my present invention is to combine in a so called automatic shoulder arm the advantages of a single fire or semi-

automatic gun with the advantages of an automatic or volley-fire gun.

With these ends in view my invention consists in a self-loading, self-ejecting and self-cocking shoulder gun having means for converting it from a single fire to a volley fire arm.

My invention further consists in certain details of construction and combinations of parts as will be hereinafter described and pointed out in the claims.

For the illustration of my invention, I have shown it as embodied in an automatic firearm constructed substantially in accordance with United States Patent No. 681,481 granted August 27, 1901. I have however, shown only those parts of the gun of that patent necessary for the disclosure of my present invention.

In carrying out my invention as herein shown I employ a sliding or longitudinally movable sear 2 having a longitudinally extended pivot-hole 3 through which the pivot 4 of the trigger 5 passes, the sear and trigger turning independently of each other upon the pivot. At its forward end the sear is formed with a cocking-nose 6 adapted to enter a cocking-notch 7 formed in the heel of the hammer 8 which is not formed with any half-cocking notch. The rear end of the sear terminates in a flattened finger 9 for coaction with a single-fire notch 10 and a volley-fire notch 11 formed in the upper rear corner of the trigger 5, the notch 11 being located in front of and below the notch 10. The notches 10 and 11 are separated by a horizontal lifting face 12 coacting with the notch 11, while a corresponding face 13 coacting with the notch 10 is located back of and above the same. Back of these notches 10 and 11 the trigger is furnished with a groove 14 for the reception of a wire trigger-spring 15 located in a spring-chamber 16 formed in the lower tang 17 of the gun frame 18. At its forward end the sear 2 is furnished with an offsetting volley-fire finger 19 having its front face formed with a bevel 20 for coaction with a bevel 21 at the rear end of a volley-fire lever 22 which rocks upon the hammer-pivot 23. The forward end of the said lever 22 is formed with a cam-like projection 24 entering a long groove 25 having its rear end curved to form a cam 26 coacting with the projection 24 aforesaid. The groove 25 aforesaid is formed in part in the bal-

anced breech block 27 and in part in the right hand forwardly extending arm 28 thereof. The said volley-fire lever 22 and groove 25 are constructed and arranged so that the cam 26 coacts with the rear bevel of the projection 24 just as the breech-block 27 moves into its closed or recoil-taking position.

The trigger 5 has a socket 29 formed in it for the reception of a yielding trigger-stop 30 in the form of a plunger resting upon a spiral volley-fire spring 31 located in the bottom of the socket 29 and exerting a constant effort to push the stop out of the socket in which it is held by a retaining pin 32 entering a notch 33 in the top of the stop. The upper face of the rear end of the stop 30 engages at the point 34 with the lower end of rear wall of a vertical recess or cut 35 formed in the tang 17 for the reception of the trigger 5. This engagement of the stop 30 with the rear wall of the recess 35 limits the swinging movement of the trigger in the use of the gun as a single-fire gun, the spring 31 being made stiff enough to prevent the stop from yielding and moving forward except when the user of the arm consciously exerts unusual force in pulling the trigger to the rearward when the spring 31 will be compressed, allowing the stop 30 to move forward and the trigger be lifted into its volley-fire position.

A helical sear-spring 36 located in a bore 37 in the trigger 5 enters a shallow recess 38 in the sear and exerts a constant effort not only to move the sear bodily forward within the limits of its elongated pivot-hole 3, but also to lift the cocking nose 6 of the sear as high as it will go into the cocking-notch 7. The said sear-spring 36 is lighter than the hammer-spring 39 which, as will appear later on, overcomes the tension of the sear-spring 36 in moving the sear bodily rearward.

Having now detailed the construction of the particular form of my invention chosen for illustration, I will proceed to set forth its operation. After the pulling of the trigger 5 has withdrawn the cocking-nose 6 from the cocking-notch 7, the sear-spring 36 will immediately move the sear 2 bodily forward with the effect of carrying the finger 9 and at its rear end forward beyond the range of the horizontal lifting-seat 12 forming the lower part of the single-fire notch 10, and therefore beyond the operative range of the trigger. Now as the action of the gun in re-cocking is automatic, the pulling of the trigger and the explosion of the cartridge is almost instantly followed by the re-cocking of the hammer which is effected by the entrance of the cocking nose 6 of the sear into the cocking-notch 7 by the agency of the sear-spring 36 which exerts a constant effort to lift the nose of the sear as well as to slide the sear bodily forward. If, now, the rear-

ward draft upon the trigger is not removed by the relaxation of the finger which pulled it, the sear will be moved bodily rearward by the hammer-spring 39 acting through the forward wall of the cocking-notch 7, and the forward edge of the cocking-nose 6 and overcoming the tension of the sear-spring 36 which is weaker than the hammer-spring 39. In this way the sear will be moved rearward until its finger 9 is abutted against the vertical wall of the single-fire notch 10. During the rearward movement of the sear as described the hammer will swing forward slightly, but that is immaterial. The gun cannot be fired with the parts in the positions just above described inasmuch as the trigger 5 is not in operative relation to the sear 2. To bring the two parts into operative relations, rearward draft upon the trigger must be removed so as to permit the trigger-spring 15 to act and swing the trigger downward so as to move its face 13 below the finger 9 of the sear which will then be moved bodily rearward by the agency of the hammer-spring 39. As the sear moves bodily rearward the hammer will swing forward again through a short arc, but this is immaterial. The gun may now be fired as a single-fire gun by pulling the trigger the face 13 of which is now in position to operate upon and lift the finger 9 of the sear, whereby the cocking-nose 6 thereof is withdrawn from the cocking-notch 7 of the hammer, so as to let the same fall. It will thus be seen that the conscious release or letting up of rearward draft upon the trigger must be interposed between each firing of the gun when the same is used as a single-fire gun.

To convert the gun from a single-fire to a volley-fire gun, the trigger is pulled upon with sufficient force to overcome the tension of the spring 31 permitting the yielding trigger-stop 30 to move forward and the trigger to be lifted high enough to bring its volley-fire notch 11 into cooperation with the finger 9 at the rear end of the sear. When this is done, (and it makes no difference whether it is done before the first cartridge has been fired or after it or any other cartridge has been fired), the vertical wall of the volley-fire notch 11 prevents the sear from being moved bodily rearward as before described, by the overcoming of the tension of the sear-spring 36 by the superior tension of the hammer-spring 39. On this account the sear is held so far forward that just as the breech-block 27 is moving into its recoil-taking position, the cam 26 of the groove 25 coacts with the beveled projection 24 of the volley-fire lever 22 the bevel 21 at the rear end of which coacts with the bevel 20 of the volley-fire finger 19 of the sear which is now depressed by its forward end so as to disengage its cocking-nose 6 from the cocking-notch 7 instead of being lifted

to accomplish the same result by means of the trigger and the finger 9 at the rear end of the sear. So long, therefore, as the trigger is held in its volley-fire position, the vertical rear wall of its volley-fire notch 11 will hold the sear forward into position for the coaction of its volley-fire finger 19 with the volley-fire lever 22 which is operated by the closing movement of the breech-block. At any time, however, that the extra tension required for volley-firing is removed from the trigger, the volley-fire spring 31 will assert itself to bring the trigger back into its single-fire position whereby the volley-fire notch 11 will be carried downward below coöperative range with the finger 9 of the sear which will then be permitted to be slid bodily rearward as before by the hammer-spring 39. In this way the gun will be converted from a volley-fire to a single-fire gun. It will be seen that all that it is necessary to do to convert the gun from a single-fire to a volley-fire gun, and vice versa, is to vary the amount of rearward draft upon the trigger. Furthermore the means required for these conversions are extremely simple and reliable.

I claim:—

1. In a gun convertible from single to volley firing, and vice versa, the combination with a trigger normally taking a single fire position, moving under extra pressure from its single firing to its volley firing position, of a longitudinally movable sear coacting with single-fire and volley-fire

notches in the trigger, a volley-fire lever coacting with the sear for operating the same automatically when the trigger is in its volley-fire position and the said lever being constructed to be automatically operated by one of the moving parts of the gun.

2. In an automatic shoulder arm convertible from a single to a volley-fire arm and vice versa, the combination with a trigger, of a yielding stop therefor, a longitudinally movable sear coacting with the trigger which prevents the bodily rearward movement of the sear when the trigger is in its volley-firing position, a volley-fire lever coacting with the forward end of the sear, and a breech-block coacting with the volley-fire lever to operate the same just as the breech-block moves into its recoil-taking position.

3. In a gun convertible from single to volley-firing and vice versa, the combination with a trigger, of a yielding stop normally holding the trigger in position for single firing but yielding to permit it to be moved into position for volley-firing, the said stop being mounted directly in the said trigger and projecting rearwardly therefrom.

In testimony whereof, I have signed this specification in the presence of two subscribing witnesses.

FRANKLIN F. KNOUS.
